CLAIM

The ornamental design for grip scissors, as shown and described.

DESCRIPTION

FIG. 1 is a front elevation of the grip scissors showing our new design with the blades in a closed position;

FIG. 2 is a rear elevation thereof;

FIG. 3 is a left side elevation thereof;

FIG. 4 is a right side elevation thereof;

FIG. 5 is a top plan view thereof;

FIG. 6 is a bottom plan view thereof;

FIG. 7 is a front elevation thereof with the blades in an open position;

FIG. 8 is a top plan view of that shown in FIG. 7; and

FIG. 9 is a right side elevation of that shown in FIG. 7.

FIG. 1

FIG. 2

FIG. 3

FIG. 4
